Term of patent 14 years

(Cl. D87—5)

(Granted under Title 35, U. S. Code (1952), sec. 266)

FIG. 1.

FIG. 2.

FIG. 3.

FIG. 5.

FIG. 4.

To all whom it may concern:

The invention described herein, if patented, may be manufactured and used by or for the Government for governmental purposes, without the payment to me of any royalty thereon.

Be it known that I, Harry G. Libbey, Jr., a citizen of the United States, residing at Arlington, in the county of Arlington and State of Virginia, have invented a new, original, and ornamental Design for a Luggage Carrier or Like Article, of which the following is a specification, reference being had to the accompanying drawing, forming a part thereof.

Figure 1 is a side elevation of a luggage carrier or like article, showing my new design;

Figure 2 is an end elevation of the same;

Figure 3 is a side elevation of the luggage carrier or like article with the lid in an open position;

Figure 4 is a plan view of the luggage carrier or like article; and,

Figure 5 is a perspective view of the same.

The dominant features of the design are shown in the drawing in full lines.

I claim:

The ornamental design for a luggage carrier or like article, substantially as shown and described.
